REVOLVING DOOR

Edmund Peremi, Manhasset, and Charles Kish, Elmhurst, N. Y., assignors to General Bronze Corporation, Long Island City, N. Y., a corporation of New York

Application February 10, 1932, Serial No. 592,004

33 Claims. (Cl. 20—18)

This invention relates to revolving doors and has for an object the provision of improved means for mounting the leaves of the door so that said leaves may be collapsed in case of emergency to permit free access through the door, or may be folded up so as to permit the door to be moved to one side of its enclosure. More particularly means are provided for pivotally supporting the leaves in such a manner that they cannot sag or get out of alignment with respect to the central column of the door, either when arranged in operative radial position or when folded. Another object of the invention is the provision of improved means for releasably securing the chains which connect the several leaves so as to hold the leaves in spaced radial position during operation of the door, but which permit of the collapse of the door in case of emergency. Another object of the invention is to provide means for governing the speed of rotation of the door so as to make it impossible for the door to be rotated at a dangerous or excessive speed. Other objects and advantages of the invention will appear from the following description of certain preferred embodiments thereof, chosen to illustrate the principle of the invention.

In the accompanying drawings which illustrate such preferred embodiments:

Figure 1 is a front elevation of the door showing the door enclosure in section;

Figure 2 is a plan view of the door with the ceiling and parts above omitted and showing the door enclosure in horizontal section;

Figure 3 is a central vertical section through the door supporting column and the hinge connections by which the leaves are pivotally mounted on such column, portions of the leaves being shown in elevation;

Figure 4 is a horizontal section on line 4—4 of Figure 3;

Figure 5 is a top plan view of the parts shown in Figure 3 showing the door leaves folded;

Figure 6 is a central vertical section through the door supporting column and top hinge connections of the leaves of a modified construction of door, parts being shown in elevation. This figure also shows a form of trolley construction for supporting the door column, the trolley being shown partly in section and partly in elevation.

Figure 7 is a view similar to Figure 6, showing the lower part of the column and lower hinge supports.

Figure 8 is a detail view, partly in vertical section taken on the center line of two leaves of the door when in radial operative position and partly

in elevation, showing the closure sleeve for closing the openings through the outer tube of the door column in the construction shown in Figures 6 and 7.

Figure 9 is a horizontal section on line 9—9 of Figure 7, showing the door leaves folded.

Figure 10 is a horizontal section on line 10—10 of Figure 6, showing the door leaves folded.

Figure 11 is a section similar to Fig. 10 showing the door leaves in radial position.

Figure 12 is a horizontal section on line 12—12 of Figure 6.

Figure 13 is a detail view in vertical section showing a door leaf chain fitting comprising releasable means for holding one of the "panic" chains which may be used to hold or assist in holding the door leaves in spaced radial position.

Figures 14, 15 and 16 are horizontal sectional views taken on lines 14—14, 15—15 and 16—16 respectively of Figure 13.

Figure 17 is a view in side elevation of a modified form of "panic-chain" fitting showing the cover plate removed.

Figures 18 and 19 are sections on lines 18—18 and 19—19 respectively of Figure 17.

Figure 20 is a plan view showing a door trolley with a governor mounted therein.

Figure 21 is a central, transverse, vertical section of the trolley and governor mechanism shown in Figure 20, parts being shown in elevation.

Figure 22 is a plan view showing a modified form of governor mounted on a door trolley, the cover plate of the governor mechanism being removed.

Figure 23 is a transverse section taken on line 23—23 of Figure 22.

Figure 24 is a detail vertical section taken on line 24—24 of Figure 22.

Figure 25 is a view partly in side elevation and partly in vertical section of another modified form of governor mounted on the door trolley.

Referring to the drawings in detail, the door enclosure consists of curved side walls 30, ceiling 31 and the floor 32 of the building. The door comprises a central column 33 on which are pivotally mounted the leaves 34. The door is supported so that the column and leaves may rotate within the door enclosure, the column preferably being suspended by means of anti-friction bearings from the trolley 40 which is mounted to travel on a track 41 supported above the ceiling 31. The ceiling 31 is provided with slot 42 through which the column passes, and the bottom of the column is provided with a retractable pivot pin 43 adapted to be received in a socket 44.

et 44 located centrally of the door enclosure. A second socket 45 is preferably provided near the side of the door enclosure to receive the pivot 43 when the door is folded and moved to one side, as shown in dotted lines in Figure 2. At one end of the track 41 and also near its center is preferably mounted a latch mechanism 46 for holding the trolley at one or the other limit of its movement. The leaves are provided with suitable weather stripping 47 so as to make a weather proof fit with the door enclosure walls, ceiling and floor.

Referring particularly to Figures 3, 4 and 5, these figures show a preferred construction for pivotally supporting the door leaves on the central column. Two hinge connections between the leaves and column are preferably provided, one located near the upper part of the door, and one near the lower part of the door. For this purpose, each of the leaves is provided with a hinge fitting 50 which is fixed in the body of the leaf. The door column comprises a strong tube 51 which is suspended from the trolley, and mounted near the upper end of this tube and firmly attached thereto is a sleeve 52 which has four arms 53 projecting therefrom in the form of a cross, each arm being provided with a radial slot 54. Similarly mounted near the lower end of the tube 51 is another sleeve 52 having arms 53 provided with slots 54. Also fixed to the tube 51 at suitable distances from the sleeves 52 are collars 55, each of which is provided with a flange 56. A thin walled metal tube 57 is preferably fitted over these flanges 56 so as to provide a finish for the visible portion of the door column. Mounted on the tube 51 between the collars 55 and the sleeves 52 are a series of flanged bushings 60 which fit end to end and fill the spaces between the sleeves and collars at the top and bottom of the door, respectively. Mounted on each of the flanged bushings 60 near the top of the door, are hinge arms or links 65, one for each door leaf. Similar but inverted hinge arms or links 66 are mounted on the flanged bushings near the bottom of the door. Each of the hinge arms is provided with a body ring 67 encircling the bushing, and the hinge arms for the different leaves are offset more or less, as clearly shown in Figure 3, so that the arm portions which engage the door leaves lie in the same plane. As will be evident, one of the four hinge arms is not offset, but lies in the same plane as its body ring. The body rings 67 are of slightly less thickness than the height of the flanged bushings 60, so that slight clearance is allowed between the adjacent body rings, as indicated at 68. Each hinge arm is pivotally connected with its door leaf by means of a pivot pin 70. These pivot pins are preferably cylindrical and are mounted to turn in openings 71 in the door hinge fittings 50. Each pin is secured in a hole in a hinge arm by means of a set screw 72, and the pins may be readily removed to permit dismounting of the door leaves by loosening the set screws. Owing to the form of the door hinge fittings, it will be seen that a long bearing is provided for each pivot pin, at each side of the arm to which it is attached, giving strength and durability. The construction described provides a double pivotal connection between each leaf and the central column, as the leaves may pivot with respect to the arms and the arms are rotatably mounted upon the column. This permits the door leaves to be closely collapsed or folded together. The leaves may all be folded into parallelism so as to pro-

ject at one side of the column, as shown in Figure 5, or the leaves may be folded into two pairs projecting in opposite directions from the column in a well understood manner. The edges of the leaves adjacent to the column and the outer wall of the column are suitably formed to provide weather proof joints when the leaves are radially extended in operative position. For example, as shown in Figures 3, and 4, the inner edge of each leaf is provided with a longitudinal rib 80 which is adapted to be received in a groove 81 when the leaf is in radial position. The depth and inclination of the walls of the groove are such that the rib 80 may rock into and out of the groove as the leaf is moved to radial position or collapsed. At the top and bottom of the door the grooves 81 are formed in the sleeves 52, while between the hinge fittings the grooves are formed in the sleeve 57. Any other suitable formation of the edges of the door leaves and column may be utilized which will provide weather tight joints.

While the links or hinge arms 65 and 66 support the door leaves and permit the necessary pivotal movement thereof, there is danger of the leaves getting out of alignment when folded, especially where heavy metal door leaves are utilized. It will be seen that each leaf is supported by a single link at the top and another link at the bottom, each of which links or hinge arms has a pivotal connection at each end. Any play or looseness of these pivotal connections, such as must inevitably be present, or any straining of the links or of the pivotal supports, makes it possible for the top and bottom of the leaf to get out of alignment with consequent jamming of the parts, or excessive friction, interfering with the proper folding of the leaf. In order to overcome this difficulty, it is important to provide means which will effectually maintain the proper vertical alignment between the top and bottom of each leaf during its pivotal movement. In the construction shown, the means provided for this purpose comprises the slotted cross-arms 53 already described, one of which is mounted near the top and one near the bottom of the door. Each door leaf is provided with guide pins 85 mounted in the hinge fittings 50 at the top and bottom of the leaf, which pins slide in the corresponding slots 54 in the cross-arms 53. As the sleeves 52 and cross-arms 53 are fixed with relation to one another, it will be seen that the slots 54 will properly guide the pins 85, and therefore the tops and bottoms of the leaves are always in true vertical alignment. The engagement of the pins in the fixed guide slots also constrains the leaves and links to movement in determinate paths when the leaves are folded.

In order to enable the leaves to be folded closely without interference from the ends of the arms, recesses 90 are provided in extension portions of the hinge fittings 50 into which the ends of the cross-arms may project, as will appear from Figure 5. To prevent the passage of drafts through the recesses 90, the recesses are closed by flaps 91 mounted on spring hinges 92 (Fig. 3).

For retaining the leaves in radial position, each leaf is preferably provided at top and bottom with a spring pressed bullet catch 94 adapted to engage in the corresponding slot 54 when the door leaf reaches the radial position. On the application of sufficient pressure to the leaf, these catches will be forced into retracted position and permit the door leaf to fold. Additional means for retaining the door leaves in radial operative

position are preferably provided, such as the releasable "panic" chains 99 (Fig. 1), which may be of any suitable construction, such for instance as one of the constructions illustrated in Figures 5 13 to 19 which will be more particularly described hereafter.

Figures 6 to 12 show a modified construction of door. 103 is the central tubular support for the door which is rotatably suspended from the trolley 40, and 104 are the door leaves. Mounted on the tube 103 are four collars 105, 106, 107, and 108 (Figs. 6 and 7). Mounted between each pair of collars are four flanged bushings 109 filling the space between the collars, and each preferably secured to the tube by suitable means such as screws 110. Rotatably mounted on each of the bushings is the body ring 111 of a hinge arm or link 112. All of the hinge arms except one are provided with an offset portion 113 so as to bring the laterally projecting parts of the arms into the same plane. Each of the door leaves is provided with hinge fittings 114 at top and bottom to receive the hinge arms. The fittings carry pivots 115 passing through holes in the hinge arms. The pivots may be lifted in their recesses in the hinge fittings so as to permit the door leaves to be dismounted. In order to secure the pivot pins in either their operative or retracted positions, each pin is provided with a screw 116 passing through a slot 117 in the corresponding hinge fitting (Fig. 7). For releasably retaining each leaf in alignment with its hinge arms when the leaves are set in radial position, each hinge fitting is provided with a spring pressed bullet catch 118 adapted to engage in a recess 119 in the corresponding hinge arm.

The mounting of the leaves upon the hinge arms with the pivotal connections between each leaf and its hinge arms and the rotative movement of the hinge arms about the central shaft permit the leaves to be folded into desired position, either with all four leaves parallel, as shown in Figures 9 and 10, or with the leaves folded two and two and extending in opposite directions 45 from the column. As pointed out in connection with the construction previously described, however, leaves pivoted merely on the hinge arms in this manner may get out of alignment in such a way as to sag or jam and prevent proper operation of the parts. In the present construction means are provided for positively maintaining the alignment of the top and bottom hinge arms for each leaf, and thus maintaining the leaves in truly vertical position at all times. This is accomplished by connecting corresponding upper and lower hinge arms by means of rigid bars 120 (Figs. 6, 7 and 9). These bars are of sufficiently heavy cross-section to resist any torsional stresses to which they may be subjected, and they are anchored to their corresponding hinge arms in a manner to resist relative turning between the arms and the bars. For instance, as shown the arms are provided with tongues 121 which fit into grooves in the ends of the bars, the bars 60 and arms being clamped together by cap screws 122. Thus each pair of hinge arms and its connecting bar become in effect a unitary hinge structure for the leaf supported thereby. As a further means for guiding the leaves during their folding movement, a plate 130 is provided which is attached to the tube 103 preferably adjacent to the top of the door, this plate having four cross-arms 131 provided with slots 132 similar to the slotted cross-arms 53 previously described. 70 In the present construction only one cross-arm 75

plate is provided because of the rigid connection between each pair of hinge arms. Each of the door leaves is provided with a guide pin 133 working in one of the slots 132. The plate 130 is provided with a neck portion 135 (Figs. 6, 10 and 11), in which are formed four recesses 136 which receive projecting ribs 137 on the edges of the door leaf guide fittings 138. The guide pins 133 are carried in these projecting portions 137. In order to enclose the bars 120 and provide a smooth and attractive finish for the central door column, and also to provide for a weather tight joint between the leaves and the column, a sleeve 140 is employed which is supported from the tube 103 by a flange 141 mounted just below the guide plate 130 (Fig. 6) and by a flange 142 mounted at the lower end of the column. The sleeve 140 is also supported at suitable points by means of braces 143 (Fig. 9). As the movement of the hinge arms and connecting bars is less than 90°, such cross-braces do not interfere with the proper functioning of the parts. The sleeve 140 is provided with horizontal slots 144 to permit movement of the hinge arms, and in order to close the portions of these slots at each side of the arms when the door leaves are in radially extended operative position, tubular shields 150 slidably fitted inside the sleeve 140 are provided (Figs. 6, 7 and 8). The upper shield (Figs. 6 and 8) normally rests on the upper hinge arms 30 and is provided with notches 151 in its lower edge leaving shield projections 152 which extend downwardly between the arms and back of the slot portions in the main sleeve 140 when the arms are in right angular spaced position. Shield 35 150 is normally held down by springs 153. The walls of slots 151 are curved as shown in Figure 8, and the arms at the point where they engage the slot walls are cut away to provide curved surfaces 154. When the arms are rotated by 40 the folding of the leaves, it will be seen that engagement of these curved surfaces with the inclined walls of the slots will exert a camming action which will push up the shield 150 so as to permit the arms to move. The lower shield 45 150 is operated in the same way as the upper shield, it being normally urged upward by means of springs 155 (Fig. 7) which are supported on spring brackets 156 attached to the central tube 103. 50

For actuating the bottom door pivot 160 (Fig. 7) and for operating the latch actuating head 161 at the top of the door (Fig. 6) rods 162 and 163 are provided, connecting these parts respectively with a slide 164 mounted in the tube 103 55 (Fig. 7). The slide 164 is actuated by means of a stud 165 which projects through bayonet slot 166 in the tube 103, and through a correspondingly placed slot 167 in the sleeve 140. The end of the stud preferably carries a hinged flush bolt 60 168 which lies in the slot 167 when not in use, but may be pivoted outwardly so as to enable the stud 165 and slide 164 to be moved. The sleeve 140 and the inner edges of the door leaves are provided with suitable means for insuring 65 weather tight joints when the leaves are in operative radial position (Fig. 12). In the construction shown the sleeve 140 is provided with ribs 170 which fit corresponding grooves 171 formed in the inner edges of the leaves. When the door 70 leaves are folded, the edges of the leaves rock away from the ribs 170 as shown in Figure 9.

Figures 13 to 16 show a releasable panic chain fastening means which may be applied to either of the door constructions described above, or to 75

any other collapsible revolving door construction in which panic chains may be utilized. Referring to these figures in detail, each door leaf is provided with a housing 200 having a recess 201 therein which is adapted to be closed by a removable cover plate 202. The housing 200 is also provided with a second recess 203 at the front of which is an apertured wall 204 through which passes a bolt 205 fastened to one end of the panic chain and secured in the recess 203 by nuts 206, thus forming a dead end for a panic chain section. Mounted in the recess 201 is a vertical shaft 210 which is journaled at its lower end in a bearing in the bottom of the recess and near its upper end in a bearing in a removable plate 211. The upper end of the shaft 212 is squared and carries a block 213 having a surface which is cylindrical, except at one side where there is a projection 214 providing a flat side 215 tangential to the cylindrical surface. The block is also provided with a recess 216 for the reception of an operating pin (not shown). The block is adapted to be locked against rotation in one direction by the engagement of the flat surface 215 with a removable plate 217, but being capable of rotation through a part of a turn in the other direction. Fixed to the shaft and to the housing are two coiled springs 220, and by removing the locking plate 217 and rotating the shaft these springs may be given any desired tension which will be maintained by replacing the locking plate so as to engage the flat side of the block as described. The block is so arranged as to prevent the rotation of the shaft in a direction to release the tension of the springs, but will permit the partial rotation of the shaft in a direction to increase such tension. Fixed to the shaft 210 between the springs 220 is a star wheel 222. The free end of each chain section 99 is provided with a head 225 which carries a tooth 226 adapted to engage between two of the star wheel teeth, the length of the chain being preferably so adjusted that the tooth 226 will hold the star wheel, shaft 210 and block 213 in such a position that the flat face 215 is out of contact with the plate 217 as shown in Figure 16. It will be seen that the tensioned springs tend to rotate the shaft and star wheel in a counter-clockwise direction (Fig. 14), and thereby to draw the head 225 into the recess in the housing, so as to maintain the chain 99 taut. However, upon the application of sufficient force to the chain 99, as would be caused by substantial pressure applied to the door leaf to which the other end of the chain section is attached, the star wheel will yield sufficiently to release the tooth 226, and thereby release the chain and attached door leaf. The star wheel is provided with sockets 227 which may be engaged by pins, so as to rotate the shaft and place the springs 220 under the desired initial tension.

Figures 17 to 19 show another construction for releasably holding the end of a "panic-chain" section. As here shown, each door leaf is provided with a housing 240 in which is a recess 241 covered by a cover plate 242. Each housing is provided with means for holding the dead end of one chain section and with releasable means for engaging the free end of another chain section. For the latter purpose a latch block 243 is mounted in the recess 241 (Fig. 18), and is provided with a lug 244 adapted to engage with the diamond shaped head 245 fixed to the free end of the chain section 99. Pivoted in a slot 246 in the housing by a pivot 247 is a latch 248 which

has a nose 249 adapted to engage with the diamond shaped head 245 on the chain, and to releasably retain such head in the housing in cooperation with the lug 244. The pivoted latch 248 is normally held with the nose advanced by means of a coiled compression spring 250. The pivoted latch 248 is also provided with a finger piece 251 by which it may be swung about its pivot so as to move the nose 249 away from the head 245 when it is desired to manually release the chain. The latch block 243 is urged towards the head 245 and normally held in its advanced position in contact with a fixed stop 255 by means of an adjustable screw 256 which is carried by a lever 257 pivoted at one end upon a fixed pivot 253. The other end of the lever is constantly urged towards the right (Fig. 17), by means of a strong coiled tension spring 259, one end of which is connected to the lever and the other end to a fixed pin 260. With the parts in the position shown in Figure 18, it will be seen that tension applied to the chain section 99 will cause the diamond shaped head 245 to engage the nose 249 on the pivoted latch 248. As the nose projects beyond the pivot 247 at this time, the tension will not release this pivoted latch, but will hold it firmly in the position shown. Increased tension on the chain section will, however, cause the diamond shaped head 245 to force the lug 244 and block 243 to the left against the tension of spring 259 and thereby release the chain. If it is desired to manually release the chain, it is not necessary to apply this degree of force to the chain, as the application of light pressure to the finger piece 251 will rotate the latch 248 so as to free the chain 99 without the application of any substantial force thereto. Preferably the spring supported block 243 which carries the chain engaging abutment 244, which is adapted to yield to release the chain in case of panic, is located nearer to the outer edge of the door leaf than is the abutment 249 which does not yield to a pull on the chain. As the chain makes an angle of 45° with the door leaf it will be seen that the force of the pull of the chain falls more heavily on the relatively fixed abutment 249 than on the yielding abutment 244. Accordingly the yielding force of the spring 259 necessary to hold the abutment 244 in place is less than in constructions where the yielding abutment is located on the side of the chain nearest the center of the door. A light spring may accordingly be used.

In order to provide governing means for preventing the door from being revolved at excessive speed, a suitable governor construction may be applied to the door. A governor construction which may be utilized for this purpose is illustrated in Figures 1, 20 and 21. In the construction here illustrated, a type of centrifugal governor is employed which is carried on a bracket 280 attached to the trolley 40. The governor comprises a housing 281 fixed to the bracket and having four downwardly and inwardly extending wall portions 282 united at the bottom and carrying a bearing 283. Mounted on top of the housing 281 is a spider 284 carrying an upper bearing 285. Rotatably mounted in these bearings is a vertical shaft 286 which has a pinion 287 fixed to its lower end, which is in constant mesh with a gear 288 fixed to the rotatable column 33 of the door. The shaft 286 has fixed to it a collar 290 which carries two projecting slotted arms 291. Passing through the slots in these arms, and pivoted on pivots 292 carried by the collar, are a pair of bell crank levers 293 carrying weights 294.

at their lower ends. Also carried by the collar 290 are two arms 295 projecting at right angles to the arms 291. Carried in the ends of the arms 295 are brake shoe pivots 296 on each of which 5 is pivoted a pair of brake shoes 297 which are adapted to be forced into engagement with the fixed brake drum 298 carried by the housing 281. The free ends of the brake shoes 297 are operatively connected with the upper arms of the bell 10 crank levers 293 by means of bell cranks 300 pivoted upon pins 301 carried by the arms 291, the overlapping ends of the bell cranks being pivoted to yokes 302 by means of pivot pins 303. These 15 yokes are connected to the upper ends of the bell crank levers 293 by means of adjustable links 304. When the speed of rotation of the door, which is transmitted to the shaft 286, reaches the maximum desired, the outward movement of the weights 294 will cause the brake shoes to be applied 20 and thereby retard the speed of the door.

In Figures 22, 23 and 24 a modified form of 25 governor is illustrated in which a brake drum 310 is mounted on the door trolley by means of brackets 311, the top of the drum being closed by a 30 cover 312. Mounted in bearings in the drum and cover is a vertical shaft 313 on the lower end of which is fixed a pinion 314 which meshes with the gear 315 fixed to the upper end of the door column 33. Mounted on the shaft 313 within 35 the brake drum is a spider 320 having two arms 321, to each of which is pivoted a brake shoe 322. The spider 320 has two other arms 325 projecting at right angles to the arms 321, each of these arms having a dove-tail or otherwise suitable shaped guide 326 at the top thereof on 40 which is slidably mounted a weight 327 adapted to engage one of the brake shoes. Each of the arms 325 is also provided with an upwardly projecting lug 328, and each of the weights has a groove 329 in its upper surface. A pin 330 is attached to each brake shoe and passes through the groove in the top of the corresponding weight and through a hole in the corresponding lug 328. Mounted on the inner end of each pin is a coiled 45 compression spring 331 which is retained in position by adjustable nuts 332. Also mounted on each pin is a stop collar 333, adapted to engage the corresponding lug 328 and limit the inward movement of the pin. The rotation of the door 50 will rotate the column 33 which will drive the vertical shaft 313 through the gearing described and thus rotate the spider 320 and the weights and brake shoes carried thereby. The centrifugal force of the weights will overcome the 55 resistance of the springs 331 and will cause the brake shoes to be applied to the inner vertical wall of the brake drum 310. By adjusting the nuts 332, the resistance of the springs 331 can be adjusted so that the braking force will be applied at 60 the proper speed to check the motion of the door. The construction described is very compact and, as will be seen, the brake drum is mounted above the trolley and tracks and very little lateral space is required to receive it. By mounting the gear 315 on the upper end of the door column 65 above the trolley, no space is required to be left between the trolley tracks and the ceiling for the reception of this gear, but the tracks may be seated directly upon the ceiling if desired.

In Figure 25 another form of governor is shown comprising a frame 340 mounted on the door trolley and carrying a vertical shaft 341 which has fixed to its lower end a pinion 342 meshing with a gear 343 on the upper end of the door column 33. Adjustably mounted on a

table 345 on top of the bracket 340 by means of studs 346 and nuts 347 is a conical drum 348 carrying a conical brake band 349. Slidably mounted on the shaft 341 is a sleeve 350 which is caused to rotate with the shaft by means of a pin 351 working in grooves 352 in the sleeve. The sleeve carries at its lower end a conical brake shoe 353 which is adapted to be brought into engagement with the conical brake band 349 by means of two levers 355 carrying weights 356 and 10 pivoted by pivots 357 to a collar 358 fixed to the upper end of the shaft 341. Links 359 connect the levers 355 with the sleeve 350.

While we have illustrated and described in detail certain preferred forms of our invention, 15 it is to be understood that changes may be made therein and the invention embodied in other structures. We do not, therefore, desire to limit ourselves to the specific constructions illustrated, but intend to cover our invention broadly in what- 20 ever form its principle may be utilized.

We claim:

1. In a revolving door, a central supporting column, a plurality of door leaves supported on said column in such manner that they may be 25 fixed in radial position or collapsed, the means for so mounting the leaves comprising hinge arms pivotally mounted on said column and pivoted to the respective leaves, a guide plate fixed to said column and having a plurality of guideways therein, and a guide member on each leaf travelling along one of said guideways and co-operating with the hinge arms carrying said leaf to constrain said leaf to move in a predetermined path when folded to collapse said door. 35

2. In a revolving door, a central supporting column, a plurality of door leaves supported on said column in such manner that they may be fixed in radial position or collapsed, the means for so mounting the leaves comprising hinge arms 40 pivotally mounted on said column and pivoted to the respective leaves, a guide plate fixed to said column having radial guideways therein, and a guide member on each leaf travelling in one of said guideways to guide the leaf during folding 45 to collapse said door.

3. In a revolving door, a central supporting column, a plurality of door leaves supported on said column in such manner that they may be fixed in radial position or collapsed, the means 50 for so mounting the leaves comprising hinge arms pivotally mounted on said column and pivoted to the respective leaves, a guide plate fixed to said column having radial guideways therein, a pin on each leaf travelling in one of said guideways 55 to guide the leaf during folding to collapse said door, and means for maintaining the hinge arms for each door leaf in alignment during folding.

4. In a revolving door, a central supporting column, a plurality of door leaves supported on said column in such manner that they may be fixed in radial position or collapsed, the means for so mounting the leaves comprising hinge arms pivotally mounted on said column and pivoted to the respective leaves, guide plates fixed to said 60 column near the ends thereof and having aligned guideways therein, each of said leaves having a pair of pins travelling respectively in a pair of said aligned guideways for maintaining the proper vertical alignment of said leaves during folding 65 to collapse said door.

5. In a revolving door, a central supporting column, a plurality of door leaves supported on said column in such manner that they may be fixed in radial position or collapsed, the means for so 75

mounting the leaves comprising hinge arms pivotally mounted on said column and pivoted to the respective leaves, a cross-shaped guide plate fixed to said column having radial guide slots in the cross-arms thereof, a guide pin on each leaf travelling in one of said slots and a recess in each leaf adapted to receive the end of a cross-arm when the leaf is folded.

6. In a revolving door, a central supporting column, a plurality of door leaves, hinge arms pivotally mounted on said column and pivoted to the respective leaves, a cross-shaped guide plate fixed to said column having radial guide slots in the cross-arms thereof, a guide pin on each leaf travelling in one of said slots and a recess in each leaf adapted to receive the end of a cross-arm when the leaf is folded, and yielding flaps for closing said recesses.

7. In a revolving door, a central column, a plurality of door leaves supported on said column in such manner that they may be fixed in radial position or collapsed, the means for so mounting the leaves comprising upper and lower groups of hinge arms pivotally mounted on said column, one of said door leaves being mounted on each pair of hinge arms, vertical bars rigidly connecting each pair of hinge arms to maintain the same in alignment, and guide means for constraining said leaves to move in predetermined paths while being folded.

8. In a revolving door, a central column, upper and lower groups of hinge arms pivotally mounted on said column, door leaves mounted on each pair of hinge arms, vertical bars rigidly connecting each pair of hinge arms to maintain the same in alignment, a guide plate fixed to said column, guideways in said plate and pins carried by portions of said leaves nearer to said column than the pivotal connections between said leaves and the hinge arms when said leaves are in radial position, one of said pins travelling in each of said guideways.

9. In a revolving door, a central column, upper and lower groups of hinge arms pivotally mounted on said column, door leaves mounted on each pair of hinge arms, vertical bars rigidly connecting each pair of hinge arms to maintain the same in alignment, and a sleeve carried by said central column enclosing said vertical bars.

10. In a revolving door, a central column, upper and lower groups of hinge arms pivotally mounted on said column, door leaves mounted on each pair of hinge arms, vertical bars rigidly connecting each pair of hinge arms to maintain the same in alignment; and a sleeve carried by said central column enclosing said vertical bars, said sleeve being slotted for passage of said hinge arms and shields for closing said slots at each side of said hinge arms when the door leaves are set in radial position.

11. In a revolving door, a central column, upper and lower groups of hinge arms pivotally mounted on said column, door leaves mounted on each pair of hinge arms, vertical bars rigidly connecting each pair of hinge arms to maintain the same in alignment, and a sleeve carried by said central column enclosing said vertical bars, said sleeve being slotted for passage of said hinge arms and shields for closing said slots at each side of said hinge arms when the door leaves are set in radial position, said shields each comprising a tubular member supported upon springs and having notches in one end adapted to receive said hinge arms, said arms and notches having inclined engaging surfaces whereby, when said

arms are moved from radial position, they will force said shield into retracted position.

12. In a revolving door, a central supporting column, a plurality of door leaves supported on said column in such manner that they may be fixed in radial position or collapsed, the means for so mounting the leaves comprising hinge arms pivotally mounted on said column and pivoted to the respective leaves, a guide plate fixed to said column having radial guideways therein, and a guide member on each leaf travelling in one of said guideways to guide the leaf during folding, and bullet catches on the leaves adapted to engage in said guideways when the leaves are in radial position.

13. In a revolving door, a central supporting column, a plurality of bearing bushings mounted thereon, a plurality of hinge arms each having a ring portion surrounding and pivotally mounted and supported upon one of said bearing bushings independently of the adjacent hinge arms and door leaves pivotally attached to said hinge arms.

14. In a revolving door, a central supporting column, groups of flanged bearing bushings mounted near the upper and lower ends of said column, a plurality of hinge arms each having a ring portion surrounding one of said bearing bushings and supported by the flange thereof out of contact with the adjacent ring portions, and door leaves pivotally mounted upon pairs of said hinge arms.

15. In a revolving door, a panic chain construction comprising a chain, a fitting mounted in a door leaf, a shaft mounted in said fitting, a rotatable chain engaging latch member mounted on said shaft and within the leaf and adapted to release the chain by a partial rotation, a spring for yieldingly resisting the rotation of said latch member so as to releasably hold said latch member in engagement with the chain, and means accessible from the exterior of the leaf for turning said latch within the leaf to a releasing position, whereby the chain may be released without tensioning the chain.

16. In a revolving door, a panic chain construction comprising a fitting mounted on a door leaf, a vertical shaft rotatably mounted in said fitting, a star wheel mounted on said shaft, a coiled spring fixed at one end to said shaft and at the other end to said fitting and adapted to yieldingly resist the rotation of said shaft, and a chain section having an end piece adapted to be releasably engaged by the teeth of said star wheel.

17. In a revolving door, a panic chain construction comprising a fitting mounted on a door leaf, a vertical shaft rotatably mounted in said fitting, a star wheel mounted on said shaft, a coiled spring fixed at one end to said shaft and at the other end to said fitting and adapted to yieldingly resist the rotation of said shaft, a chain section having an end piece adapted to be releasably engaged by the teeth of said star wheel, and means for adjusting the tension of said spring.

18. In a revolving door, a panic chain construction comprising a fitting mounted on a door leaf, a vertical shaft rotatably mounted in said fitting, a star wheel mounted on said shaft, a coiled spring fixed at one end to said shaft and at the other end to said fitting and adapted to yieldingly resist the rotation of said shaft, said shaft carrying a block having a stop surface thereon limiting rotation of said shaft in one direction but permitting partial rotation thereof in

- a direction to increase the tension of said spring, and a chain section having an end piece adapted to be releasably engaged by the teeth of said star wheel.
- 5 19. In a revolving door, a panic chain construction comprising a fitting mounted in a door leaf, a chain section, and a pair of clamping members in said fitting for engaging the end of said chain section, means for operating one of 10 said members manually to release said chain section and means for yieldably holding the other of said members in engagement with said chain section, said means permitting said member to move and release said chain section on the application of a predetermined force.
- 15 20. In a revolving door, a panic chain construction comprising a fitting mounted in a door leaf, a chain section, and a pair of clamping members in said fitting for engaging the end of 20 said chain section, one of said members being pivotally mounted and being provided with means whereby it may be manually moved about its pivot to disengage said chain section and the other of said members being yieldingly supported 25 in engagement with the end of said chain section by means permitting said member to yield and release said chain section upon the application of a predetermined force thereto.
21. In a revolving door, a panic chain construction comprising a fitting mounted in a door leaf, a chain section, and a pair of clamping members in said fitting for engaging the end of 30 said chain section, one of said members being pivotally mounted and being provided with means whereby it may be manually moved about its pivot to disengage said chain section and the other of said members comprising a block mounted to slide in a recess in said door fitting, and yieldable means for holding said block in engagement with the end of said chain section, said yieldable means comprising a pivoted lever and a spring for holding said lever in engagement with said block.
- 35 22. In a revolving door, a trolley, a door column rotatably suspended therefrom and carrying door leaves, a bracket carried by said trolley, a fixed braking member carried by said bracket, a rotatable member carried by said bracket, means for driving said rotatable member from said door column, brake shoe means carried by said rotatable member, and centrifugal means for causing 40 said brake shoe means to be engaged with said fixed braking member on the rotation of said door at excessive speed.
- 45 23. In a revolving door, a trolley, a door column rotatably suspended therefrom and carrying door leaves, a bracket carried by said trolley, a fixed braking member carried by said bracket, a rotatable member carried by said bracket, means for driving said rotatable member from said door column, including a gear fixed to said door column above said trolley, brake shoe means carried by said rotatable member, and centrifugal means for causing said brake shoe means to be 50 engaged with said fixed braking member on the rotation of said door at excessive speed.
- 55 24. In a revolving door, a trolley, a door column rotatably supported thereby, a bracket on said trolley, a housing carried by said bracket, a brake drum carried by said housing, a vertical shaft rotatably mounted in said housing, gearing for driving said vertical shaft from said door column, a spider mounted on said rotatable shaft, brake shoes carried by said spider, and centrifugal means carried by said spider for 60 forcing said brake shoes into engagement with said brake drum.
25. In a revolving door, a trolley, a door column rotatably supported thereby, a bracket on said trolley, a housing carried by said bracket, a brake drum carried by said housing, a vertical shaft rotatably mounted in said housing, gearing for driving said vertical shaft from said door column, a spider mounted on said rotatable shaft, brake shoes carried by said spider, and 10 centrifugal means carried by said spider for forcing said brake shoes into engagement with said brake drum, said centrifugal means comprising weighted bell crank levers carried by said spider and linkage operatively connecting said 15 bell crank levers with said brake shoes.
26. In a revolving door, a trolley, a door column rotatably supported thereby, a bracket on said trolley, a housing carried by said bracket, a brake drum carried by said housing, a vertical 20 shaft rotatably mounted in said housing, gearing for driving said vertical shaft from said door column, a spider mounted on said rotatable shaft, brake shoes carried by said spider, and centrifugal means carried by said spider for forcing 25 said brake shoes into engagement with said brake drum, said centrifugal means comprising weights engaging said brake shoes and mounted to slide radially on said spider.
27. In a revolving door, a trolley, a door column rotatably supported thereby, a bracket on said trolley, a housing carried by said bracket, a brake drum carried by said housing, a vertical shaft rotatably mounted in said housing, gearing for driving said vertical shaft from said door 30 column, a spider mounted on said rotatable shaft, brake shoes carried by said spider, and centrifugal means carried by said spider for forcing said brake shoes into engagement with said brake drum, said centrifugal means comprising 35 weights engaging said brake shoes and mounted to slide radially on said spider, and adjustable spring means for resisting the outward movement of said weights.
28. In a revolving door, a rotatable door column and a governor therefor comprising a bracket, a vertical shaft mounted therein, gearing for driving said vertical shaft from said door column, a fixed conical brake member carried by said bracket, a sleeve slidably mounted on 40 said shaft, a conical brake shoe carried by said sleeve, and centrifugal means for moving said sleeve longitudinally of said shaft to cause the conical brake shoe thereon to engage with said fixed conical brake member.
29. The combination with a revolving door, of an overhead supporting carriage therefor, a track supporting the carriage, a shaft for said door, an oscillatable support for said shaft and door upon said carriage, a friction speed controlling device mounted wholly as a self-contained unit upon and travelling with said carriage, and driving connections between said shaft and said device, said device being mounted above the track in position to avoid interference with 55 the tilting of said support.
30. The combination with a revolving door, of a shaft therefor, a carriage supporting the door, and a speed controlling device for said door mounted wholly as a self-contained unit upon 60 and travelling with said carriage and door, said speed controlling device comprising a friction drum and centrifugally controlled friction means cooperating with the drum.
31. The combination with a revolving door of 75

- a shaft therefor, a carriage supporting the door, and a speed controlling device for said door mounted wholly as a self-contained unit upon and travelling with said carriage and door, carriage locking means for retaining the door in normal operating position comprising cooperative locking parts, one of which is carried by the carriage, and an unlocking rod extending upward through the door shaft for engaging and releasing one of said locking parts, said controlling device being disposed out of alignment with the door shaft and in non-interfering relation to the unlocking rod and the locking parts.
32. The combination with a revolving door having wings, of a shaft therefor, a carriage supporting the door, a speed controlling device for said door mounted wholly as a self-contained unit upon and traveling with said carriage and door, a door enclosure including arcuate side walls and a ceiling having a radial slot therein for accommodating the door shaft, a carriage supporting track above the ceiling extending in the direction of the radial slot, said door including means collapsibly supporting the door wings upon the shaft so that the wings may be folded and then moved with the shaft to one side of the door enclosure comprising a horizontally disposed drum mounted eccentrically with relation to the door shaft, and centrifugally controlled friction devices cooperating with said drum, and said speed controlling device being confined so as not to extend a greater distance from the center of the door enclosure in the direction of the radial slot than the wing supporting means extends in that direction, whereby interference by the speed controlling device

with the movement of the collapsed door toward one side of the door enclosure is avoided.

33. The combination with a revolving door having wings, of a shaft therefor, a carriage supporting the door, a speed controlling device for said door mounted wholly as a self-contained unit upon and traveling with said carriage and door, a door enclosure including arcuate side walls and a ceiling having a radial slot therein for accommodating the door shaft, a carriage supporting track above the ceiling extending in the direction of the radial slot, said door including means collapsibly supporting the door wings upon the shaft so that the wings may be folded and then moved with the shaft to one side of the door enclosure, said speed controlling device including a horizontally disposed drum eccentrically mounted with relation to the door shaft, a vertical shaft concentric with the drum, and a pinion on the vertical shaft, and gearing including a relatively large driving gear on the door shaft for driving said pinion, and centrifugally controlled members driven by the vertical shaft within the drum and cooperating with the drum, said carriage, driving gear, and drum being all confined and mounted so as not to extend to a greater distance from the center of the door enclosure in the direction of the radial slot than the wing supporting means extends in that direction, whereby interference by the speed controlling device with the movement of the collapsed door toward one side of the door enclosure is avoided.

EDMUND PEREMI.
